WILLIAM R. COPPAGE, OF WASHINGTON, DISTRICT OF COLUMBIA, ASSIGNOR OF ONE-HALF TO H. N. BRAWNER, JR., OF WASHINGTON, DISTRICT OF COLUMBIA.

BOTTLE-WASHING MACHINE.

1,207,866.

Specification of Letters Patent. Patented Dec. 12, 1916.

Application filed August 28, 1914. Serial No. 859,108.

To all whom it may concern:

Be it known that I, WILLIAM R. COPPAGE, of Washington, District of Columbia, have invented certain new and useful Improvements in Bottle-Washing Machines; and I do hereby declare the following to be a full, clear, and exact description of the invention, such as will enable others skilled in the art to which it appertains to make and use 10 the same.

My invention relates to an apparatus for washing bottles or jars, and more particularly milk bottles, the object being to provide means for automatically feeding the 15 bottles to the apparatus, actuating the washing devices to thoroughly cleanse the bottles inside and out, and automatically discharging the bottles from the apparatus, and it consists in the parts and combination of 20 parts and in the details of construction as will be more fully explained and pointed out in the claims.

In the accompanying drawings, Figure 1 is a view in transverse section of my im- 25 proved apparatus; Fig. 2 is a view in plan of a section of the apparatus, a portion of the top being broken away; Fig. 3 is a view in section showing the feed trough and the means for feeding the bottles from the 30 trough to the bottle carrier; Fig. 4 is a view in section showing a bottle being dropped from a carrier into the discharge chute, and Fig. 5 is a view in section on the line $x-x$ of Fig. 4.

35 1 represents a supporting structure preferably cylindrical in shape and provided with a slanting top 2, and 3 is the bottle carrier guide, secured to the said supporting structure 1 at the top thereof parallel with 40 the conical top frame 4.

Secured to the top 2 of the support 1 is a bracket 5 which carries and supports the shaft 6, and also one end of shaft 7, the other end of said shaft 7, being mounted in 45 bearing 8 secured to the support 1. Shaft 6 is at right angles to the top 2 of the support 1, and at the center thereof, and passes through the apex of the conical top frame the axis of which latter is at right angles to 50 the slanting top of the support. This conical top frame and the bottle carrier guide, which latter is parallel with said top frame, are connected by the ring plate 9, thus forming a closed tank for holding water, in

which the bottles and brushes are submerged 55 in the operation of the apparatus.

Secured to the lower end of shaft 6 within the support 1, is the bevel gear wheel 6^a which meshes with bevel pinion 10, on shaft 7, which as before explained is mounted in 60 a bearing carried by bracket 5 and in bearing 8 on the support 1. Shaft 7 is coupled up to a suitable motor (not shown) by a belt, chain or other suitable means and is rotating at all times while the apparatus is 65 in operation. The shaft 6 is loosely mounted at its upper end in the fixed gear wheel 11, which is secured to the fixed top frame 4 at the apex of the latter, and meshes with the series of small pinions 12 on the brush 70 shafts 13. The entire series of brush shafts 13 are mounted in and carried by the conical frame 14 which is keyed to the inclined shaft 6. The lower end of frame 14 rests on ball bearing 15 carried by the upper end of 75 bracket 5, so that the shaft 6 and the parts carried thereby, are supported on the anti-friction or ball bearing. The outer edge of the revolving frame 14, is flanged or turned upwardly, as at 16, for the two fold purpose 80 of preventing the lubricating grease or oil on the gear and pinions from gravitating into the water, and also for protecting the gearing from the water. There are a series of brush shafts 13 carried by the frame 14, 85 and each shaft carries a cylindrical brush 17, the stem 18 of which is coupled to a shaft 13 by a coupling 19.

From the foregoing it will be seen that when shaft 6 is rotated, the frame 14 will 90 rotate with the shaft, and as the frame carries the shafts 13, the latter will be rotated by the engagement of the pinions 12 thereon, with the fixed gear wheel 11, and thus rotate all the brushes simultaneously.

95 Secured to the frame 14 are a series of outwardly projecting parallel arms 20, preferably of angle iron, open at the under side. A brush 17 and its stem 18, are located centrally between each pair of arms 20, and a 100 bottle carrier 21, shown best in Figs. 3, 4 and 5, is pivotally mounted at one side edge on a rod 22 carried by and under one arm 20 of each pair. Each carrier 21 is semi-cylindrical in shape, and is lined with bristles or wool or other suitable material adapted by its contact with the bottle to scrub or 105 wash the outer surface of the latter, as the

bottles are rotated by the frictional contact of the rotating brush within the same. The carrier 21 is, as before stated, mounted to swing on rod 22, and is also adapted to slide 5 longitudinally on said rod so as to carry the bottle supported by the carrier, toward the brush. This movement of the carrier is effected by the cam ring 23 secured to the underside of the conical top plate 4, and 10 the upwardly projecting lips 24 and 25 shown in Fig. 4, secured to the inner end of the carrier 21, the lip 24 bearing against the inner face of the cam ring, and the lip 25 bearing against the outer face thereof, 15 so that as the revolving frame 14, which as before explained carries the arms 20 is rotated, lip 24 bearing against the inner face of the cam ring 23, pulls the carrier 21 toward the brush, and as the mouth of the 20 bottle is in line with the brush, the bottle will be moved over or onto the brush during the first half of the revolution of the revolving frame, and is pushed away from, and off the brush during the second half of the 25 revolution. During the rotary movement of the frame 14, the carrier and the bottle, with the revolving brush therein will have been carried down into the water in the lower part of the inclined chamber and then ele- 30 vated above the same. During this movement the bottle, brush and carrier are submerged and as the rotating brush on the inside of the bottle will by its frictional contact with the bottle, shift and turn or partly 35 turn the bottle within its carrier, it will be seen that the bottle will be thoroughly cleaned inside and out during its passage through the apparatus. In its movements over the carrier guide 3, the bottle carrier 40 21 rests on and is supported by the said guide 3, and is preferably provided at its outer end as shown, with a roller 26 which rolls on said guide and reduces the friction.

The bottles to be cleaned are placed in the 45 feed trough 27, which is provided with a gage 27^a adapted to be adjusted for bottles of various sizes. The bottles are placed in the inclined trough with their necks on the gage, as shown in Fig. 1, and are held at the 50 lower end of the trough by the yielding fingers 28. The top plate 4 is cut away as at 29, at the feeding point, which is adjacent the lower end of the trough, and the lower end of the latter is slotted and projects into 55 said opening and terminates just above and in close proximity to the plates 30. These plates connect the adjacent arms 20 of the several pairs at the outer ends of the latter, leaving the space between the arms of each 60 pair open for the entrance of the bottles. The rear arms 20 of each pair, are provided with a series of upwardly projecting fingers 31, which latter are so located as to pass through the slots 32 in the lower end of the 65 trough 27 and engage the bottle, that is in

contact with the yielding fingers 28, and force the same into the carrier 21. As the bottle is released from the trough, the next one moves to position to be engaged by the fingers 31 adjacent the next carrier. After 70 the bottle drops into a carrier the continued rotary movement of the latter brings the cam ring 23 into contact with the lip 24, which operates to move the carrier longitudinally toward the brush with the mouth of the 75 bottle in line with the latter. The brushes are wet from their previous passage through the water, but they, and the bottle and carrier for the latter, are, owing to the inclination of the conical container, carried 80 downwardly until submerged in the water, the brush in the meanwhile rotating in the bottle and imparting by its frictional contact with the bottle, more or less rotation to the latter, so as to clean it thoroughly inside and out. As the bottle continues its movement around the tank, it is elevated from its inclined position, as shown at the left of Fig. 1, to a nearly horizontal position 85 at point of discharge as shown in Fig. 4. 90 As the bottle carrier with the bottle therein, begins its ascent, the lip 25 on the carrier 21 is engaged by the outer face of cam ring 23, which operates to push the carrier outwardly and away from its brush, and by the time 95 the carrier reaches the discharge chute 33, the bottle and carrier 21 will have been moved clear of the brush, thus leaving the bottle free to be discharged. The discharge chute 33 is attached to the carrier guide 3, 100 and the latter is cut away, as shown in Figs. 4 and 5, so that as the carrier 21 reaches the chute it will be unsupported and drop, as in Fig. 5, and discharge its bottle into the chute, which is so inclined that the bottle 105 deposited therein slides rapidly into a rinsing machine or other container located under the lower end of the chute.

I prefer to provide the container with a water supply pipe 34, a drain and discharge 110 pipe 35, and an overflow 36, so that water either hot or cold, may be constantly supplied and a uniform level maintained. After the carrier 21 drops its bottle into the chute, the continued rotation of the frame 14, 115 causes the carrier 21 by its contact with the inclined side wall of the chute, to assume its normal position to receive the next bottle. The carrier passes from the chute to the trough for the next bottle therein and after passing around the apparatus discharges the bottle into the chute. The apparatus may have a dozen, more or less of carriers and brushes, so that the washing of a larger number of bottles may be thoroughly, rapidly and economically accomplished without any attention other than placing the bottles on the trough.

It is evident that many changes in the details may be resorted to without departing 120

from the spirit of my invention, hence I would have it understood that I do not confine myself to the details as shown, but consider myself at liberty to make such changes as may fall within the scope of my invention.

Having fully described my invention what I claim as new and desire to secure by Letters-Patent, is:—

10 1. In bottle washing apparatus, the combination of a tank, a bottle carrier in which the bottle is loosely supported, the said carrier having means for scrubbing the outer side of the bottle, means for moving said

15 carrier through the tank, a brush located in line with the carrier and movable with the same, means for moving the carrier toward and away from the brush, means above the water level in the tank for automatically

20 feeding the bottle to the carrier, and means for automatically discharging the bottle after it has passed through the tank.

2. In a bottle washing apparatus, the combination of a tank, a bottle carrier in which the bottle is loosely supported, the said carrier having means for washing the outer side of the bottle, means for moving the same down into the water in said tank and then up above the water, a revolving brush located in line with the carrier and movable with the latter, means for moving the carrier toward and away from the revolving brush means located above the water level in the tank for automatically feeding the bottles to the carrier, and means for automatically discharging said bottles after they have been passed through the water.

3. In a bottle washing apparatus, the combination of a tank, a conical frame mounted on an oblique axis so that one part of the frame will be horizontal when the diametrically opposite part thereof is immersed in said tank, a fixed inclined carrier guide partly within the tank, a bottle carrier mounted on the conical frame and adapted to move on the carrier guide and also move transversely of the latter, a revolving brush bearing a fixed relation to the bottle carrier and located in a position to enter the bottle in the carrier as the latter is moved transversely of the carrier guide, means adjacent the horizontal part of the frame for feeding bottles to the carrier, and means for discharging bottles from the carrier.

4. In a bottle washing apparatus, the combination of a tank, a fixed circular inclined guide the lower portion of which is within the water, a hinged bottle carrier mounted to travel on said guide and maintained by the same in position to support the bottle, means for moving the carrier transversely of the guide and a revolving brush located in the path of transverse movement of the bottle carrier, whereby when the bot-

tle carrier is moved transversely of the guide in one direction it will carry the bottle onto the revolving brush.

5. In a bottle washing apparatus, the combination of a water tank, a circular inclined guide the lower portion of which is below the water level in the said tank, a bottle carrier hinged at one side edge, and sustained in carrying position during its movement around the apparatus by the guide on which it moves, and adapted when it reaches the discharge point to tilt and discharge the bottle, and means for washing the inside of the bottle.

6. In bottle washing apparatus, the combination of a water tank, a circular guide within said tank, the said guide being higher at one side than the other so as to be partly above the water level in the tank, a rotating frame carrying a series of pivoted bottle carriers which are maintained in position to carry the bottles by the circular guide and a revolving brush for each bottle carrier, means for revolving the brushes and means for moving the bottle carriers toward and away from their respective brushes.

7. In bottle washing apparatus, the combination of a water tank, a circular guide therein the guide being inclined so that one part is above the water level, a rotating frame within the tank, a series of bottle carriers on said frame and moving on the circular guide, each carrier having a bottle scrubbing lining, a revolving brush for each bottle carrier, means for revolving the brushes and means for moving the bottle carriers toward the brushes during the first part of the rotary travel of the bottle carriers and away from said brushes during the latter part of said movement.

8. In bottle washing apparatus, the combination of a support having an inclined top, a tank carried by said support, a shaft at right angles to said inclined top and in line with the long axis of the cone, a frame keyed to the shaft, a series of bottle carriers carried by said frame, a revolving brush for each bottle carrier also carried by said frame, means for rotating the brushes and means for moving the bottle carriers toward and away from their respective brushes.

9. In bottle washing apparatus, the combination of a support having an inclined top, a tank on said support, and at one side thereof, a revolving frame, the axis of which is inclined, bottle carriers on said frame and adapted to pass through the tank, rotating brushes also carried by said frame, means for rotating the frame, means for revolving the brushes, and means for moving the bottle carriers toward and away from the brushes.

10. In a bottle washing machine, the combination of a water tank, a top plate having an opening through the same through which

the bottles are fed to the bottle carriers, a revolving frame below said top plate, a series of bottle carriers each mounted at one side edge on said revolving frame, whereby 5 the said carriers may tilt to discharge the bottles, the said carriers each having means for washing the outer side of the bottle, a guide on which said bottle carriers move and by which they are supported except at 10 the point where the bottles are discharged, a revolving brush for each bottle carrier, the said brushes being carried by the movable frame, and means for moving the bottle carriers toward their respective brushes and 15 also away from them at each revolution of the machine.

11. In bottle washing apparatus, the combination of a water tank, a top plate having a feed opening through the same through 20 which the bottles are fed to the bottle carrier, a revolving frame below said plate, a series of bottle carriers carried by said frame each carrier being hinged at one side edge whereby it may be tilted to discharge its bottle, a guide on which the bottle carriers move and by which they are supported except at the point where the bottles are discharged from the carriers, a chute for receiving the bottles discharged from the carriers, a revolving brush for each bottle carrier the said brushes being carried by the revolving frame, and means for moving the bottle carriers toward their respective brushes and also away from them at each 35 revolution of the frame.

12. In bottle washing apparatus, the combination of a standard having an inclined top, a tank the axis of which is at right angles to said inclined top, a frame mounted 40 to revolve within the tank on a shaft coincident with the axis of the latter, bottle carriers and brushes carried by said revolving frame, means for revolving the brushes and means for moving the bottle carriers toward the brushes.

13. In bottle washing apparatus, the combination with a tank, a shaft, a revolving frame within the tank and secured to the shaft, means for rotating the latter, a circular guide within the tank and located at an inclination so that a part of it is submerged, hinged bottle carriers carried by the revolving frame and moving on and sustained in carrying position by the guide, 50 rotating brushes also carried by said revolving frame, means for rotating the brushes, and means for moving the bottle carriers toward and away from the brushes.

14. In bottle washing apparatus the com-

bination of a tank, an inclined shaft, a 60 conical frame mounted on the shaft so that a part thereof is within the tank and the diametrically opposite part approximately horizontal and in a plane above the water in the tank, means for rotating the shaft and its frame, a series of bottle carriers, a 65 guide on which the bottle carriers move and by which they are retained in carrying positions except at the point where the bottles are discharged from the apparatus, rotating 70 brushes carried by the frame, means for rotating the brushes, and means for moving the bottle carriers toward and from the brushes.

15. In bottle washing apparatus, the combination of a tank having an opening through its top through which the bottles are fed to the bottle carriers, and an opening through which the bottles are discharged, a shaft, a revolving frame within the tank 75 and secured to the shaft, a series of bottle carriers carried by said frame, and a revolving brush for each bottle carrier, the said brushes being carried by the revolving frame, and means for moving the bottle carriers toward and away from the brushes 80 once during each revolution of the frame.

16. In a bottle washing machine, the combination of a tank, a shaft, a revolving frame within the tank and secured to the 90 shaft, a circular guide, a series of bottle carriers hinged at one side to the revolving frame and supported in carrying position by said guide, a portion of the guide being cut away so as to permit the carrier to turn 95 to a position to discharge the bottle therein, means for feeding the bottles to the carrier, a revolving brush for each carrier, and means for moving the carrier toward and away from its brush at each revolution of the revolving frame.

17. In a bottle washing apparatus, the combination of a revolving frame, a series of bottle carriers attached to said frame, each carrier having means for scrubbing the outer side of the bottle, a revolving brush 105 for each carrier, the said brushes adapted to turn the bottles on their carriers, and means for moving the carriers toward their respective brushes.

In testimony whereof, I have signed this 110 specification in the presence of two subscribing witnesses.

WILLIAM R. COPPAGE.
